United States Patent Office.

DAVID EVANS, OF STUDLEY, ENGLAND.

Letters Patent No. 63,028, dated March 19, 1867.

IMPROVEMENT IN NEEDLE-WRAPPERS.

The Schedule referred to in these Letters Patent and making part of the same.

TO ALL WHOM IT MAY CONCERN:

Be it known that I, DAVID EVANS, of Studley, in Warwickshire, England, have invented certain new and useful Improvements in the Manner of Putting up Needles in Papers or Wrappers; and I do hereby declare the following to be a full, clear, and exact description of the same, reference being had to the accompanying drawings, making a part of this specification, in which—

Figure 1 represents one of the modes of forming the flaps, sticking the needles, and folding up the paper.

Figure 2 represents the appearance of the paper of needles, as shown at fig. 1, after two folds have been made in it.

Figure 3 represents another form of paper, with the needles stuck in it, and the flaps and folding lines shown in it.

Figure 4 represents the paper, as shown in fig. 3, after two folds have been made in it.

Figures 5 and 6 show modifications of the general plans shown in figs. 1 and 3, the needles in these figures not being represented, though their position will be easily understood.

My invention consists in, in combination with the permanently fastening of the needles in the paper or wrapper, the forming the flaps which cover the heads and points (one or both) of the needles out of the same piece of paper that constitutes the wrapper for the package. The object and purpose of these flaps will be explained hereafter.

To enable others skilled in the art to make and use my invention; I will proceed to describe the same with reference to the drawings.

A represents a rectangular piece of paper, in which are cut slots 1 2 3, so as to form flaps *a*, that may be folded back or forth by the fourth side, which is uncut. The needles *c* may be stuck through a piece of tape, *e*, that is drawn through slots in, and pasted or fastened to, the paper, and both are thus very securely held to the paper. But it is not actually necessary to use tape or cloth, as the single piece of paper will serve all purposes. This piece of paper A, when folded up with the needles in it, and afterwards opened out, will show creases or folds at the horizontal dotted lines 5 6 7, and the vertical lines 8 and 9.

When the paper and the needles in it is folded at the lines or creases 5 6 it will be as shown in fig. 2, where the heads and points of the needles can be seen and are accessible by folding back the flaps *a a*; or, the flap at the points may remain closed and the thumb over it, so as to hold the needles without allowing the moisture of the thumb or finger to touch them, and endanger their corrosion, whilst the other flap is moved back to take a needle out or to replace it. To fold the paper once more, viz, at the dotted line 7, and then at the vertical lines 8 9, it forms a pocket, case, or envelope, one end being stuck into the other, and is in the usual condition of needles that are put up into papers for market, use, or transportation, and may be printed upon in any suitable manner, to designate the manufacture, kind, or name of the patentee.

In fig. 3 is shown a modification of the general plan of forming the flap out of the piece of paper that constitutes the wrapper. In this case the flaps *a a* are formed by cutting away the portions *b b*. In this case, too, there is one more horizontal fold, viz, that shown at 4. The needles in this plan, as in the other, are stuck in a piece of tape, or other fibrous material; drawn through slots in, and pasted or fastened to, the paper; and, when folded at the dotted lines 4 and 5, the package will have the appearance shown in fig. 4, where the flaps are represented as folded back to gain access to the needles, but which flaps, one or both, may be closed down upon the needles, as above stated. When folded over at the lines 6 7, and those 8 9, then the flap piece *i* may be gummed, or otherwise folded down or tucked in, and the package is formed, giving protection to the needles, and making them easily accessible to the user.

Figs. 5 and 6 represent other modifications of the form of the wrapper or pocket before it is folded up, wherein the same letters and figures of reference are used as in the other heretofore-described cases or plans. The needles are not represented as stuck in these figures, but holes are represented at *n*, where they may be stuck into the paper, and then the latter folded up, and the flaps tucked in, as in the other cases described, to hold them in their folded-up position. The flaps *a a*, in figs. 5 and 6, can also be folded over the heads and points of the needles, or thrown back to select and take out a needle from the package. The usual printing may be done on the paper, or on labels and pasted thereon, as may be preferred.

Having thus fully described my invention, what I claim in putting up needles in paper, is—

The fastening and folding up of the needles in wrappers or papers that have flaps and folds, as herein shown, so that the needles are easy of access from the outside, without liability to drop or fall from the wrapper, or to corrosion from contact with the fingers, as herein described and represented.

DAVID EVANS.
